HEDDLE BAR LOCK FOR LOOMS

George F. Bahan, Charlotte, N. C.

Application December 19, 1933, Serial No. 703,139

13 Claims. (Cl. 139—92)

This invention relates to an improved heddle bar lock which is particularly adapted for use with heddle frames employed in conjunction with looms.

One object of the invention is to provide a heddle bar lock which will be of such construction that a heddle bar carried therein will be effectually retained against undesirable lateral or longitudinal shifting movement, but which lock employs a latch member which will permit ready disengagement of the heddle bar from the lock when desired.

Another object of the invention is to provide a device of this character which will be self-contained so that none of its parts will project laterally beyond the extremities of the housing employed.

A further object of the invention is to provide a heddle bar lock which will be extremely simple in construction but which will be durable in use over long periods of time without attention.

A still further object of the invention is to provide a heddle bar lock which will consist of but few parts.

And the invention seeks as a still further object to provide a heddle bar lock wherein the latch member will be formed with a jaw which will serve to urge the heddle bar inwardly so that danger of accidental slipping of a heddle bar from the lock will be eliminated.

It is thought that other and incidental objects of the invention will render themselves apparent during the course of the following description.

My invention is illustrated in the accompanying drawing, wherein,

Figure 1 is a front view of the lower portion of a heddle frame with a number of my improved heddle bar locks thereon.

Figure 2 is an enlarged vertical sectional view of one embodiment of my heddle bar lock showing the type to be employed intermediate the heddle frame.

Figure 3 is a front elevation view of the heddle bar lock showing a portion of a heddle bar therein.

Figure 4 is a horizontal sectional view taken on the line 4—4 of Figure 2 looking in the direction indicated by the arrows.

Figure 5 is a perspective view of the latch member employed with my heddle bar lock.

Figure 6 is a vertical sectional view showing a slightly modified form of my heddle bar lock.

Figure 7 is a horizontal sectional view taken on the line 7—7 of Figure 8 and looking in the direction indicated by the arrows, and

Figure 8 is a fragmentary sectional view showing a form of the heddle bar lock employed at the ends of the heddle frame.

Referring now more particularly to the accompanying drawing wherein like numerals of reference designate like parts throughout the several views, the numeral 1 indicates the bottom rail of a heddle frame, and 2 the metal end pieces thereof. Tubular connecting pieces 3 are held in place in the end pieces by the means of bolts 4. A conventional heddle bar is shown at 5. My improved heddle bar lock includes, in one embodiment, a screw 6 which is adapted to be sunk into the wood of the heddle rail 1 and is formed with a rectangular upwardly extending head 7. A slightly enlarged base 8 which cooperates with the head 7 to define a shoulder 9 is provided at the junction of said head and screw. The head 7 is provided at its upper end with a flat upper surface.

Normally tightly fitted about the rectangular head 7 of the screw 6 is a preferably tubular rectangular housing which is indicated in general by the numeral 10, the lower end of the housing being adapted to abut the shoulder 9 of the base 8 so that the outer surface of said housing will be normally in the same vertical plane with the outer surface of the base 8. A smooth surface from the base to the upper extremity of the housing is therefore provided. It is pointed out that the head 7 projects upwardly within the housing a sufficient distance so as to provide a substantial mounting therefor so that danger of accidental disengagement of the housing from the head will be avoided. Formed in the housing at one side thereof, which I shall designate as the forward side, is a substantially rectangular opening 11 which is of a height substantially equal to the height of a heddle bar to be carried within the device and of a depth equal to slightly over one-half the width of the housing.

Formed in the walls defining the opening, at the junction of the upper edges and vertical rear walls of said opening, are aligned circular notches 12 which are adapted to receive the upper edge 45 of a heddle bar. Formed on the forward side of the housing at its upper extremity and originally projecting above the housing is a lip 13, the purpose of which will be described hereinafter. In order to retain a heddle bar in proper position 50 in the housing, I employ a latch member which is indicated in general by the numeral 14. The latch member is shown in detail in Figure 5 of the drawing and includes a lower portion 15 having a flat lower surface 16, and said lower por- 55

tion is formed with a tooth or jaw 17 having inclined sides 17' which lower jaw cooperates with the vertical portion 18 of the latch member to define a groove 19 which is adapted to receive the lower circular edge of the heddle bar. The latch member is of a width at its upper and lower portions sufficient to fit slidably but snugly within the housing 10; however, the vertical portion 18 is of only a sufficient width to extend to close spaced relation to the vertical rear walls of the opening 11 so that the heddle bar will be permitted to lie against the inner walls of the opening in close spaced relation to the forward wall of the vertical portion 18. The upper portion of the latch member, which is indicated at 20, is formed with a finger-engaging portion 21 which extends above the upper end of the housing 10 and is formed with beveled edges for manual engagement. As seen clearly in Figure 2 of the drawing, the upper portion is cut away at its forward side to define a shoulder 22. After the latch member has been placed within the housing, the lip 13 is bent inwardly to overhang the shoulder 22 so that its lower edge will be adapted to cooperate with said shoulder 22 for defining a stop. Thus, upward movement of the latch member will thereby be effectually controlled.

Carried within the housing and located between the flat lower surface 16 of the latch member and the flat upper surface of the head 7, is a spring 23 which serves normally to urge the latch member upwardly within the housing. The spring may be of the coiled type as shown, or may be an S shaped leaf spring as shown at 47 in Fig. 8. As will be understood, this particular embodiment of my invention is adapted for use intermediate the rails of the heddle frame and, after said device has been screwed into the rails, a heddle bar is first inserted with its upper circular edge extending into the alined notches 12 in the opening 11 and the lower edge is then swung inwardly within the opening and will engage the inclined walls of the tooth 11 for urging the latch member downwardly against the tension of the spring 23. As soon as the lower extremity of the heddle bar has passed over the point of the tooth or jaw 17, the latch member will be moved upwardly by the tension of the spring for clamping the heddle bar tightly between the groove 19 in the latch member and the notches 12 in the housing. It will be seen that the heddle bar will be effectually held against longitudinal or lateral shifting movement within the heddle bar lock as the tooth will effectually grasp the lower edge of the heddle bar and tend to urge it against the inner walls of the opening 11.

When it is desired to release the heddle bar from the lock, it is only necessary to depress the finger-engaging portion 21 for urging the latch member downwardly and freeing the tooth from the lower edge of the heddle bar. The lower edge of the heddle bar may be swung outwardly and then the upper edge removed from the notches. The bar may then be completely withdrawn from the opening 11.

Referring now to the modification of my invention, as shown in Figure 6 of the drawing, I employ a screw 24 having a stepped head 25 which is formed with a retaining lip 26 at the upper extremity of the vertical central wall defining the step. The head 25 is provided with a base 27 which is enlarged to define a shoulder 28. A housing 28', of substantially twice the size 75 of the housing shown in the preferred form of

the invention, fits snugly about the head 25 at its lower extremity flush with the outer surface of the head and its lower edge seated against the shoulder 28. Formed in the housing 28', at both sides thereof, are openings 29 and 30 which are of the same configuration as the opening 11 of the preferred form, but the opening 29 is located in a plane slightly lower than the plane of the opening 30. Lips 31 and 32 are formed on the upper extremity of the housing, at opposite sides 10 thereof. Carried in the housing and adapted to overhang the lower portion of the stepped head 25 is a latch member 33 which is of the same general form as the preferred form of the invention, but which is formed with an elongated 15 upper portion 34, the upper end of which projects above the housing to define a finger-engaging portion 35. A tooth 36 on the latch and a notch 37 in the housing are provided for retaining a heddle bar in the opening 29. A spring 20 38 normally urges the latch member upwardly within the housing and said upward travel of the latch member is limited by the lip 31 engaging a shoulder 39 which is formed by cutting away a portion of the upper end of the latch 25 member, in the manner identical with that shown at 22 in the preferred form of the invention. The spring 38 is held in proper position beneath the latch member by means of a depending lip 40 which is formed by extending downwardly, for a slight distance, the rear wall of the latch member. A second latch member 41 is carried within the housing 28' and is of identical construction with the latch member of the preferred form, but is disposed in an opposite direction to the latch member 33 and is disposed to receive and secure a heddle bar entering the opening 30 in the manner identical with the preferred form of the invention. In this form of the invention, it will be understood that two 40 heddle bars may be supported by the same heddle bar lock and may be individually controlled by simply depressing the respective upper end portions. A spring 42 which is held in place at its lower extremity by the flange or lip 26 urges the latch member 41 upwardly for engaging the tooth of said latch member with the heddle bar and effectually retains said heddle bar in position in the opening 30. Aside from the fact that the modified form of the invention provides mounting means for two heddle bars, the operation of the invention is identical with that of the preferred form in every respect.

Referring now to the modified form of the invention as shown in Figures 7 and 8, I employ a housing 43 which is of nearly identical construction with the housing 10. However, the lower end of the housing 43 is cut away at one side slightly, as indicated at 44. Carried in the housing 43 is a bracket 45 which is adapted to receive 60 the lower end portion of the housing 43 snugly thereabout. A lateral flattened portion 46, as best seen in Figure 1 of the drawing, is adapted to extend between the end piece 2 and the tubular connecting piece 3 so that the heddle bar lock 65 may be effectually supported at the end of the rail of the heddle frame, being tightly clamped in place by the bolt 4. The operation is identical with the operation of the preferred form of the invention, and it should be understood that a heddle bar lock of the type shown in Figure 6 70 of the drawing, may be employed, it being only necessary to use the bracket having an upstanding portion large enough to receive and tightly 75

hold the double width housing employed in the structure shown in Figure 6.

My heddle bar lock is characterized by extreme simplicity and durability inasmuch as there are but few working parts thereto. It may be used over long periods of time without attention. Attention is also directed to the fact that the device is very compact and will take up but a small amount of space on the heddle frame.

10 It is thought that the construction and operation of my improved heddle bar lock will be understood from the foregoing description, taken in conjunction with the several figures of the drawing and further description is, accordingly, 15 thought to be unnecessary.

Having thus described the invention, I claim:

1. A heddle bar lock including a screw, a housing carried by the screw and having a lip, a latch member slidable within the housing and held 20 against upward displacement by the lip, said housing having an opening, and a spring carried in the housing and normally urging the latch member upwardly, said latch member being adapted to removably secure a heddle bar within 25 the opening in the housing and being depressible against the tension of the spring for permitting release of the heddle bar from the opening.

2. A heddle bar lock including a screw having a rectangular head provided with a base, a housing carried by the screw and having a portion surrounding the head and terminating with its outer surface normally flush with the outer surface of the base, said housing having an opening, 30 a latch member slidable within the housing and having a vertical portion disposed to align with the walls defining the opening, said latch member being formed with a tooth cooperating with the vertical portion for defining a groove, a lip carried by the housing at its upper end and 35 adapted to cooperate with the latch member for preventing upward displacement thereof, said tooth cooperating with a heddle bar for removably retaining said heddle bar within the opening, and a spring carried within the housing and normally urging the latch member upwardly, said latch member being depressible against the tension of the spring for permitting release of the heddle bar from the housing.

3. A device of the class described including a 40 housing, a bracket supporting the housing and having an upstanding portion normally receiving the lower end portion of said housing, said bracket being formed with a lateral portion adapted for disposition between the end piece 45 and a tubular connecting piece of a heddle frame, and means carried by the housing for removably locking a heddle bar against shifting movement in the housing.

4. A heddle bar lock including a housing having an opening provided with a notch, means mounting the housing on a rail of a heddle frame, said means being formed with a head, a latch member mounted in the housing, a spring mounted in the housing between the latch member and the head and being adapted for normally urging the latch member upwardly, said latch member having a tooth, and a lip cooperating with the latch member for preventing upward displacement of the member, said latch member being 50 adapted to retain a heddle bar between the notch in the opening and the tooth whereby accidental shifting movement of the heddle bar will be prevented, said latch member being depressible against the tension of the spring for releasing the heddle bar from the opening.

5. A heddle bar lock including a screw having a rectangular head, a tubular rectangular housing having its lower portion fitted about the head, said housing having a rectangular opening formed in its upper end portion and being formed with a lip at its upper end, a latch member slidably mounted within the housing and having a finger-engageable portion cut away on its forward side to define a shoulder, said lip being bent inwardly to overhang the shoulder and forming a stop whereby upwardly sliding movement of the latch member will be limited, and a spring carried within the housing beneath the latch member and above the head, said spring being adapted for normally urging the latch upwardly for retaining a heddle bar within the opening against shifting movement, said finger-engageable portion being depressible for releasing the heddle bar from the opening.

6. A heddle bar lock including a housing, means 20 securing the housing to a heddle frame, said housing being formed with a rectangular opening having a notch therein, a latch member slidable in the housing and having a vertical portion adapted to confront the opening, said latch member being 25 formed with a tooth normally extending into the opening in the housing and having inclined sides, and a spring carried within the housing and normally urging the latch member upwardly, the inclined sides of said tooth being adapted for permitting ready passage of a heddle bar to locked position in the opening with its upper edge in the notch.

7. A heddle bar lock including a housing, a bracket mounting the housing and having an upstanding rectangular portion fitting within said housing, said bracket being formed with a lateral portion adapted for clamping between an end piece and a tubular connecting piece of a heddle frame whereby the lock may be effectually mounted on the end of a heddle frame, and means carried by the housing and adapted for removably mounting a heddle bar therein.

8. A heddle bar lock including securing means having a stepped polygonal head, a housing carried by the securing means and having its lower portion surrounding the head, said housing having oppositely presented openings, and latch members carried by the housing and being oppositely presented for removably securing heddle 50 bars in the openings.

9. A heddle bar lock including a screw having a stepped polygonal head, a housing mounted on the head and being formed with openings, latch members relatively slidable within the housing, means carried on the housing for limiting upward shifting movement of the latch members, and springs carried within the housing between the stepped head and the corresponding lower ends of the latch members, the latch members being 60 adapted to cooperate with the walls defining the openings for removably retaining a heddle bar secured to said housing.

10. A heddle bar lock including a housing, means securing the housing to a heddle frame, 65 said housing being formed with an opening defining walls having aligned notches, and a latch member slidably mounted in the housing and having a tooth adapted to cooperate with a heddle bar for clamping a portion of said bar with its upper 70 edge bridging the aligned notches and its lower edge behind said tooth whereby shifting movement of said heddle bar will be prevented.

11. A heddle bar lock including a securing means for attachment to a rail and having a 75

head polygonal in horizontal cross section, a polygonal housing fitting tightly around the head and having a lateral opening to receive a heddle bar, and means within the housing to engage and retain the heddle bar therein.

12. A heddle bar lock including a screw insertable in a rail and having a rectangular base and a rectangular head, a rectangular housing fitting tightly around the head and against the base flush with the base, the housing having a lateral opening to receive a heddle bar, and a slidible

latch enclosed in the housing to retain the heddle bar therein.

13. A heddle bar lock including an anchoring member having a flat-sided head, a flat-sided housing fitting tightly around the head and having a lateral opening to receive a heddle bar, and a slidible latch enclosed in the housing and constructed to pass around and engage a heddle bar and retain the same in the opening in the housing.
